(57) **CLAIM**

The ornamental design for a lightning rod assembly, as shown.

DESCRIPTION

FIG. 1 is a perspective view of a lightning rod assembly showing my new design;

FIG. 2 is a left side elevational view of the present invention; FIG. 3 is a right side elevational view of the present invention;

FIG. 4 is a front elevational view of the present invention; FIG. 5 is a rear elevational view of the present invention; FIG. 6 is a top plan view of the present invention; and, FIG. 7 is a bottom plan view of the present invention.

The structures shown in broken lines form no part of the claimed invention.
